Primary Examiner—Robert C. Spangler

[57] CLAIM

The ornamental design for a purse or similar article, substantially as shown and described.

DESCRIPTION

FIG. 1 is a front perspective view of a purse or similar article, showing my new design;

FIG. 2 is a side elevational view;

FIG. 3 is a rear perspective view;

FIG. 4 is a top plan view;

FIG. 5 is a bottom plan view; and,

FIG. 6 is a front perspective view with the top flap folded back.

The adjustable belt is omitted in FIGS. 2, 4 and 5 for convenience of illustration.

FIG. 1

FIG. 2

FIG. 3

FIG. 4

FIG. 5
